UNITED STATES PATENT OFFICE

92,695

DESIGN FOR A NECKTIE HOLDER

Joseph S. Bear, Detroit, Mich.

Application May 4, 1934, Serial No. 51,688

Term of patent 3½ years

To all whom it may concern:

Be it known that I, JOSEPH S. BEAR, a citizen of the United States, residing at Detroit, in the county of Wayne and State of Michigan, have invented a new, original, and ornamental Design for a Necktie Holder, of which the following is a specification, reference being had to the accompanying drawing, forming part thereof.

Fig. 1 is a perspective view of the necktie holder showing my new design.

Fig. 2 is a section taken on line 2—2 of Fig. 1 to show the form of the hooks.

I claim:

The ornamental design for a necktie holder, as shown and described.

JOSEPH S. BEAR.
